PULL FOR SLIDE FASTENER

Frank L. Hurteau, 3314 Macaulay St., San Diego, Calif.

Filed Mar. 3, 1961, Ser. No. 64,140

Term of patent 14 years

(Cl. D17—8)

FIG. 1

FIG. 2

FIG. 3

FIG. 4

FIG. 5

FIG. 6

FIGURE 1 is a perspective view of my pull for slide fastener showing the chain broken away for convenience of illustration;

FIGURE 2 is a top plan view thereof;

FIGURE 3 is a side elevational view thereof;

FIGURE 4 is a front elevational view showing in dotted lines the other end of the chain;

FIGURE 5 is a rear elevational view thereof;

FIGURE 6 is a bottom plan view.

The chain has been broken away in FIGURES 1, 3 and 5 for convenience of illustration.

I claim:

The ornamental design for a pull for a slide fastener, as shown and described.
